J. STANTHORP.

Candle Mold.

No. 12,492.

Patented March 6, 1855.

UNITED STATES PATENT OFFICE.

JOHN STAINTHORP, OF BUFFALO, NEW YORK.

MACHINE FOR MAKING CANDLES.

Specification of Letters Patent No. 12,492, dated March 6, 1855.

To all whom it may concern:

Be it known that I, JOHN STAINTHORP, of Buffalo, in the county of Erie and State of New York, have invented a new and useful Machine for Molding Candles, which I term a "Clasp and Piston Candle-Molding Machine"; and I do hereby declare that the following is a full, clear, and exact description of the construction and operation of 5 the same, reference being had to the annexed drawings, making a part of this specification, in which—

Figure 1 is a perspective view; Fig. 2 a sectional elevation; Fig. 3 a section showing 10 the application of the center mold; and Fig. 4 a face view of the clasp as applied to the tip-bar.

Let similar letters refer to like parts in 15 all the figures; then A will represent the mold stand which may be made of any desired size or form; B, the slide to which the pistons are secured; C C, etc., the molds which are fitted at their tips for the pistons, or center molds and secured firmly in the 20 stand A; D D, etc., the pistons which are provided with their tip molds (E E, etc.) and all nicely fitted to the main molds (C C, etc.) these pistons have an aperture 25 for the wick to pass through in this tip (E E) and are made hollow, however it is not absolutely necessary that they should be 30 hollow as the wick might be passed out at the side in a flute in them, or a small aperture might be made in the side of the main 35 aperture in the tip of the main mold to allow the wick to pass through without injury when the candles are ejected by the pistons this small aperture being covered by the 40 tip molds (E E) when the pistons are down;—E E, etc., the tip molds on the pistons (D D, etc.); F F, etc., the arms or levers firmly fixed to the pistons and connected together by the bar or rod X by pivots which 45 allow the bar X to work laterally; the object of this arrangement is to loosen all the candles in a row at one movement of X, this is accomplished by all the pistons being set in the slide (B) with screws or threads or other devices which by turning thus will 50 raise them slightly and thereby loosen the candles in the molds, however this is not found necessary in all cases.

G G G (Fig. 1) show the balls of wicking which should be boxed or put in tin cannisters that they may be kept dry and clean; 55 H H, the ways or guards to steady and keep

in place the slide B in its movements; I I, the pulleys over which the rope or cord runs, by which the slide B with pistons D D, etc., are raised in ejecting the candles; K, the treadle to which the foot is applied in working the piston. Instead of using the treadle, cord and pulleys, to raise the pistons and eject the candles I sometimes use a foot or hand lever in which case the power is 60 applied more direct. L the block in which the cord is secured. M M, the racks into which the candles are ejected when thrown from the molds by the pistons; N N (Fig. 2), the hinges securing the racks to the stands A; O O, the hinges securing the tip bars to the rack; P P, the tip bars are provided with cavities R R for the tips of the candles to rest in and from these cavities 65 there are ganes passing out the rounded or outer edge of the bars so that in swinging or turning these bars under the candles the wicks are each passed into its ganes and the cavities brought immediately under the candles. To accomplish this suppose the 70 candles ready for ejection, the tip bars are thrown out as shown by the dotted lines Y Y (Fig. 2).

When the candles are ejected by the pistons as before described and before the pistons are lowered, the racks are inclined to the right and left sufficient to allow the tip bars to swing under as shown in (Fig. 1). When the racks are raised perpendicular 75 the candles falling into the cavities in the tip bars when the pistons are dropped, thereby straining the wicks. Q, Q, the holes in the slats of the racks into which the candles are ejected.

S S, etc., represent the candles in the 80 racks; T T T, the wick extending from the balls to the candles at V V V as strained; V, the position of the racks when the candles are dropped into a base or canvas, dotted lines W W, etc. (Fig. 2) is to show the 85 position of the slide B with pistons when the slide is raised as in ejecting the candles; Z Z, a part of the frame work on which the racks are secured.

Fig. 4 is a face view of the wick clasps 90 which are secured to the underside of the tip bar and are connected together by the rod O and work on pivots the same as the bar and arms F F F on the pistons, but these are used for the purpose of securing 95 and retaining the upper end of the wicks, in case it is desirable to take the candles out

of the racks before filling the molds with melted tallow or other material. This clasping the wicks is accomplished by passing the bar *c* to *d* when the wicks will be 5 clasped between *e e e* and *f f f* at *E E E*.

Having thus fully described my invention what I claim as new and desire to secure by Letters Patent is—

1. The employment of the pistons *D D* 10 formed at their upper ends into molds for the tips of the candles, in combination with stationary candle molds, to throw out the

candles in a vertical direction, substantially as herein set forth.

2. I do not claim the use of clasps separately considered but I do claim, the combination of the rack tip bar, and clasps, constructed and arranged substantially as described, and for the purposes specified. 15

JOHN STAINTHORP.
